GAUGING DEVICE

Willis Fay Aller, Dayton, Ohio, assignor to The Sheffield Corporation, Dayton, Ohio, a corporation of Ohio

Application November 1, 1943, Serial No. 508,559

4 Claims. (Cl. 33—143)

1

This invention relates to thread gauges. One object of the invention is the provision of a gauge for measuring or comparing the pitch diameter of a threaded workpiece, and having work holding means for centering the workpiece to insure an exact perpendicular relation between the workpiece axis and the direction of movement of a work operated member which moves the indicating mechanism.

Another object is the provision of a thread gauge having work carrying arms providing centers which hold the workpiece so that its axis is in a definite predetermined exact position, enabling the pitch diameter of the thread to be gauged between two anvils, with a single wire arranged on each of the anvils.

Another object is the provision of a thread gauge of the character mentioned, in which the work is centered by two arms that are relatively fixed against pivotal movement on a common carrying shaft which is axially movable in a bearing having a definite fixed axis insuring an accurate predetermined position of the work axis.

Another object is the provision of a thread gauge incorporating a base and a relatively adjustable gauge unit, the base providing a support for a unitary attachment which provides a vertically movable lower work anvil and a pivot support for work holding arms.

Another object is the provision of a thread gauge having a gauge unit and a base which not only supports the gauge unit but which also provides a support for a vertically movable lower work anvil that can be quickly moved upwardly to permit the application or removal of the work.

Another object is the provision of a thread gauge having relatively movable anvils, one of which operates an indicator, the anvils having readily removable wire carriers each of which provides limited bodily movement of a single wire, the wire carriers having down turned ears which overlie the ends of the wires to prevent more than a limited amount of longitudinal movement of the wires.

Other objects and advantages of the invention will be apparent from the following description, the appended claims and accompanying drawing, in which:

Fig. 1 is the front elevation of a thread gauge embodying the present invention;

Fig. 2 is a side elevation of the gauge, a portion of the base and anvil being shown in central vertical section;

2

Fig. 3 is a top plan view of the thread checking unit or gage attachment;

Fig. 4 is a vertical section on the line 4—4 of Fig. 2;

Fig. 5 is a front elevation of the work centers and the wire holders with relation to a threaded workpiece which is shown in dotted lines;

Fig. 6 is a view of the wire holders showing the wires in association with a threaded workpiece, and

Fig. 7 is a perspective view of a wire holder.

Referring more particularly to the drawing, in which the same reference numerals have been applied to like parts in the several views, 10 designates the base and 11 a column which projects upwardly from the base and forms the support for a vertically adjustable gauge unit 12. The column 11 is provided with a vertical rack 13 engaged by a suitable pinion controlled by hand wheel 14 which is rotatably mounted on the gauge unit. A hand wheel 15 serves as a clamp, securing the indicator unit in any position to which it is adjusted on the column. The indicator unit may be of any suitable character, preferably providing visual indications on a scale that can be viewed through the opening 16, the indications being produced by the movements of a vertically operable plunger 17.

The base 10 is provided with a seat or guideway 19 adapted to receive a removable block 20 forming an anvil member in which is mounted a vertically movable work anvil 21. The seat or guideway 19 may form the support for an ordinary flat top anvil which may be used in conjunction with the indicator unit for checking sizes of objects placed directly between the plunger 17 and the anvil, but when the gauge is to be used for checking the pitch diameter of a threaded part, the conventional anvil is removed and the anvil member 20 applied to the base 10 and held rigidly in place by screws 22 the ends of which engage V-shaped grooves in the sides of this block.

Rigidly fixed at one end of the block 20, preferably as an integral part of the block, is an upstanding post 23 formed integrally with opposed guideways 24 and 25 in which the vertically adjustable plate 26 is mounted. A clamp screw 27 threaded in guideway 25 and engaging an angular face on the slide 26 holds the latter in its adjusted position. This slide 26 carries a block 29 which is connected to a vertically movable operating member 30, shown as a block having an abutment surface 31 engaging the lower end 55 of the plunger 17, and having an anvil 32 adja-

cent the work position. A pair of parallel flexible straight spring blades 33, each fixed at one end to the block 30 and at the other end to block 29, support the block 30 for yielding movement to a limited extent determined by the spacing between a projection 34 on block 30 and a notch 35 on the block 29. When the gauge unit 12 is moved on the column 11, a corresponding adjustment is given to the block 29 and the slide 26 on the post 23 which carries them. Thus the distance 10 between the anvil 32 and the lower anvil 21 can be adjusted to accommodate threaded workpieces of different diameters.

The post 23 is provided with a journal or bearing 36, preferably formed integrally therewith so that the axis of the bearing 36 cannot be changed, this axis being arranged in a plane which is perpendicular to the direction of movement of the plunger 17 and the work supporting anvil. Slidably mounted in the journal or bearing 36 is a shaft 38, so that the shaft can either rotate on its own axis or can move axially. A pair of arms 39 and 40 are provided on this shaft 38, the arm 40 preferably being fixed to the shaft, while the arm 39 is slidably movable on the shaft to vary its distance from the arm 40. A thumb screw 41, threaded in the hub portion of arm 39, can be screwed against the shaft to hold the arm 39 properly spaced from the arm 40, in accordance with the length of the workpiece to be checked, the latter being carried between a center 42 on the arm 39 and a center 43 in the arm 40. The center 43 is spring pressed towards the left as viewed in Fig. 3 and is connected to the handle 44 which the operator can pull to retract the center 43 and permit the workpiece to be conveniently mounted in place. When the operator releases the handle 44 the center 43 moves endwise into engagement with the workpiece.

The two arms 39 and 40 have extensions 46 and 47 respectively which project to the opposite side of the shaft 38. A rod 48, parallel to and spaced from the shaft 38 is secured at one end in the extension 47, while the extension 46 has a bore in which the rod 48 is slidably mounted. The rod 48 thus serves to interconnect the two arms 39 and 40 to prevent any relative angular turning of these arms with respect to one another, while permitting the distance between the two arms to be readily adjusted. The rod 48 and the extending portions 46 and 47 of the two arms also constitute a counterbalance to partially balance the weight of the workpiece and the weight of the arms. As will be apparent, the only pivotal movement of the arms to move the workpiece is one that takes place about the center of the shaft 38, the bearing of which is definitely fixed with respect to the base, so that the axis of the workpiece will be horizontal at all times, and at right angles to the direction of movement of the gauging plunger. Since the shaft 38, and thus the arms 39 and 40 are freely movable in the direction of the axis of the shaft 38, the workpiece may be readily moved in an axial direction so that any desired part of the workpiece can be checked or compared by comparing the indications produced on the gauge unit with the indication given when a workpiece of standard or required size is placed in the gauge.

The center of the shaft 38 is preferably somewhat higher than the center of a workpiece of small diameter which is applied to the arms 39 and 40, but the distance between this center

and the axis of the workpiece is such that a large range of workpiece diameters can be accommodated while maintaining the center of the workpiece above some portion of the flat upper surface of the work supporting anvil 21. It should also be noted that the post 23 is arranged adjacent the column 11 and at the opposite side of the workpiece from the operator's position, to afford clear vision, convenient access and compactness in arrangement.

The lower anvil 21, as shown in Fig. 4, has a bearing member 59 slidably guided in a cylindrical opening 51 in the anvil block 20. A compression spring 52 yieldingly urges the anvil 21 upwardly to a predetermined definite position, indicated in Fig. 4. The anvil 21 has a transverse passage 55 providing a flat surface 53 which engages a flat surface on a rotatable rod 54 extending through the passage in the anvil. The rod 54 is of cylindrical form where it extends through the anvil block 20, the center of the rod, and thus the center of rotation, being indicated at 56, see Fig. 4. At its forward end, the rod 54 is fastened to a hand lever 54'. The opposite end of the rod is grooved and the groove is engaged by a locating screw 57 in the anvil block, holding the rod against endwise movement but permitting rotational movements. Where the rod extends through the opening 55, the rod has a curved portion 58 opposite the flat surface, so that by turning the rod thru about 180° from the position shown in Fig. 4 the anvil is cammed downwardly, bringing the curved portion 58 against the surface 53 on the anvil, the parts being held in this position until the lever 54' is manually turned to release the anvil and permit the spring to force it upwardly into gauging position. A suitable stop definitely limits the upward travel of the anvil so that its gauging position will not change. In the construction shown this stop is provided by the flat surface on the rod 54 although other suitable stop means may be provided for this purpose. By retracting the anvil, the space between anvil 21 and the upper anvil 32 is increased, permitting the workpiece to be conveniently applied between the centers 42 and 43. The work is then rested on the lower anvil, moving bodily about the axis of the shaft 38 as it does so. Then the operator turns the lever 54' so as to move the parts into the position shown in Fig. 4, the lower anvil 21 rising to a definitely fixed gauging position.

The threaded workpiece is gauged with wires of known diameter, placed between the workpiece and the upper and lower anvils 32 and 21 respectively. Since the workpiece axis is definitely held in a predetermined fixed attitude, only two wires need be used, one between the workpiece and the upper anvil and the other between the workpiece and the lower anvil, the wires having a known diameter so as to contact the thread sides adjacent the pitch diameter location. The lower wire, shown in Fig. 7 at 59 is held loosely in a spring ring 60 so that it can move endwise and also move bodily in any lateral direction, to a limited extent. The ring 60 is preferably a single arcuate strip of spring metal of a diameter so that it can hold itself on the cylindrical outer surface of the anvil 21, and is provided with upwardly extending and overturned ears 61, the upwardly extending portion of the ears having horizontally elongated slots 62 permitting freedom of movement of the wire 59 in all directions, to a limited extent. The overturned portions 61 of the ears extend down 70 opposite the ends of the wire and keep the wire

from falling out of the ears. When the spring clamp 60 is applied to the lower anvil, the wire 59 rests flat on the anvil and is free to be positioned by the threaded workpiece. The same kind of a spring holder 63 is attached to the upper anvil 32, and holds the upper wire 64. The positions of the slots in the spring holders is such that the upper wire is arranged to have freedom of movement from a normal position which is somewhat offset with respect to the normal position of the opposing wire, to an extent substantially equal to one-half of the lead of the thread.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A thread gauge comprising a base having a readily removable anvil block, a work anvil axially movable in said block, a gauge unit mounted on said base, a work operated member for operating said gauge unit, a pair of work carrying arms having centers adapted for engagement with opposite ends of a threaded workpiece, a shaft on which said arms are relatively adjustable to vary the spacing between said centers, means relatively fixing said arms against relative angular motion, said block providing a fixed bearing at one side of said work anvil in which said shaft is mounted for axial and rotational movement.

2. A thread gauge comprising a base having a readily removable anvil block, a work anvil axially movable in said block, a gauge unit adjustably mounted on said base for movement towards and from said work anvil, a work operated member for operating said gauge unit, means rotatably mounted in said block for quickly raising and lowering said work anvil, a pair of work carrying arms having centers adapted for engagement with opposite ends of a threaded workpiece, a shaft on which said arms are relatively adjustable to vary the spacing between said centers, means relatively fixing said arms against relative angular motion, said block providing a fixed bearing at one side of said work anvil in which said shaft is mounted for axial and rotational movement.

3. A thread gauge comprising a base, a column on said base, a gauge unit adjustably mounted on

said column, a block removably fixed on said base and having a movable work anvil, said block having a post rigid therewith and arranged closely adjacent said column, said post providing a bearing, a shaft rotatably mounted in said bearing and axially movable therein, a pair of work carrying arms on said shaft and relatively adjustable thereon to vary the spacing therebetween, said arms having work centers adapted for engagement with opposite ends of a threaded workpiece, a bar parallel to said shaft and spaced therefrom and engaging both of said arms to prevent relative angular movement thereof.

4. A thread gauge comprising a base, a column on said base, a gauge unit adjustably mounted on said column and having a work operated plunger, a block removably fixed on said base and having a movable work anvil, means carried by said block for quickly raising and lowering said anvil, said block having a post rigid therewith and arranged closely adjacent said column, said post providing a bearing, a shaft rotatably mounted in said bearing and axially movable therein, a pair of work carrying arms on said shaft and relatively adjustable thereon to vary the spacing therebetween, said arms having work centers adapted for engagement with opposite ends of a threaded workpiece, and a bar parallel to said shaft and spaced therefrom and engaging both of said arms to prevent relative angular movement thereof.
